EQUALIZING VALVE

Mordica O. Johnston, Glendale, Calif.

Application June 13, 1936, Serial No. 85,081

6 Claims. (Cl. 166—1)

This invention relates to oil well tools and particularly pertains to an equalizing valve structure.

In the operation of various oil well tools which embody the use of a packer by which a fluid seal is created in a well between a column of fluid standing above the packer and the fluid entrapped beneath the packer, such for example, as might occur in the operation of that class of tools known as formation testers, an equalizing valve is used. A valve of this type is shown in Patent No. 1,842,270, issued to me on the 19th day of January, 1932, and entitled Oil well testing device. In this structure a bypass of fluid may be established from the areas beneath the seated packer to the fluid column thereabove or vice versa, or depending upon the relative hydrostatic pressures of the two fluids. In some instances it might be desirable to lock the equalizing valve so that a bypass fluid flow may or may not take place in order to accomplish various operations, and it is the principal object of the present invention to provide an equalizing valve of the type here disclosed which may be manipulated from the top of the well to be opened and closed, and may be furthermore manipulated from the top of the well to be temporarily locked in its closed or in its opened position.

The invention is illustrated by way of example in the accompanying drawing in which:

Figure 1 is a view in vertical section showing a well packer and an equalizing valve of the type here disclosed with the packer seated and the valve locked in its closed position.

Fig. 2 is a view in vertical section similar to that shown in Fig. 1 with the packer seated and the equalizing valve in its opened position.

Fig. 3 is a view in transverse section through the valve structure as seen on the line 3—3 of Fig. 1 indicating the position of the spline and the shoulder when the valve is locked.

Fig. 4 is a view in transverse section along the line 4—4 of Fig. 2 indicating the spline and the shoulder when they are in their locked positions.

Fig. 5 is a fragmentary view in section showing the lower portion of the tubular mandrel and the locking shoulder, and further disclosing the relation of these parts with the splines which are indicated in dotted lines.

Referring more particularly to the drawing, 18 indicates a drill string carrying a tubular mandrel 11 at its lower end. This mandrel extends into a sleeve 12 which is threaded at its lower end to a coupling 13 attached to an upper fitting 14 of a packer 15. The packer here shown is of

the rat-hole type. It will be understood that the invention may be used with equal efficiency with other types of packers, such for example as a sleeve packer, or a hooked wall packer. The packer is provided with a central tubular member 16 extending through the packing element and secured at its lower end to a coupling nut 17 which carries a perforated nipple or anchor pipe 18. The coupling 13 is formed with a central passageway 19 through it so that a fluid flow 10 may be established from below the seated packer into the perforated nipple 18 and then upwardly through the pipe 16 into the packer fitting 14 and then through the passageway 19 of the coupling 13 to a central passageway 20 within the sleeve 12 and then through the tubular mandrel 11 to the passageway through the drill string 10. The tubular mandrel 11 is formed with a circumferentially arranged row of openings 21 through its wall, which openings are normally closed when the mandrel is telescoped into the sleeve 12, as shown in Fig. 1, and are in register with the passageway 22 in a packing nut 23 when the mandrel 11 and the sleeve 12 are in the positions shown in Fig. 2 of the drawing. The packing nut 23 is 25 threaded into the upper end of the sleeve 12 and tightens packing 24 around the mandrel 11 to prevent leakage. The upper portion of the nut embodying the space 22 is formed with an end wall having perforations 25 through it. Thus 30 when the mandrel 11 is in its uppermost position a communication will be established through perforations 25 to the passageway 22 and then through perforations 21 into the tubular mandrel. In this way the hydrostatic pressure of fluid in 35 the column above the seated packer will be equalized with the hydrostatic pressure of fluid below the packer.

In some instances it is desirable to lock the equalizing valve in an opened or closed position 40 so that the flow of fluid may or may not be maintained irrespective of vertical movement of the drill string, and so that certain tests and other operations might be carried on with or without equalization of the fluids within the well above 45 and below the seated packer as the circumstances may justify. It may be desirable also to lock the equalizing valve so that it will not accidentally change position as the tool is being lowered into the well or removed therefrom. For that purpose 50 an enlarged head 26 is formed on the lower end of the tubular mandrel 11. It is shown in Fig. 5 of the drawing as being substantially cylindrical, and as providing a square face 27 for a purpose to be hereinafter explained. This head is formed 55

with longitudinally extending keyways 28 which have a circumferential length of approximately 60°. This makes it possible for limited rotation of the tubular mandrel 11 and the sleeve 12 to take place while at the same time maintaining these members in splined relation to each other so that manipulation of various elements, such as the release of the cage of a hooked wall packer, might be effected from the top of the well. Extending longitudinally within the bore 30 of the sleeve 12 is a plurality of splines 31. These splines terminate a distance short of the length of the bore 30 at opposite ends sufficient to form annular spaces 35 and 36 to accommodate the head 26 when it has moved beyond opposite ends of the splines 31 to make it possible to rotate the tubular mandrel 11 so that the shoulders 27 will be out of register with the splines 31 so that when the head 26 of mandrel 11 is in position in either of the annular spaces 35 or 36 movement of the drill stem and the tubular mandrel 11 will not be accompanied by relative movement between the tubular mandrel 11 and the sleeve 12. It will be understood that if desired the meeting edges of the ends of the splines 31 and the co-operating faces 27 of the head 26 may be inclined so that relative rotation of the tubular mandrel 11 within the sleeve 12 will produce a wedging and locking action to more firmly hold the parts against relative movement when the head 26 is in either of the annular spaces 35 or 36.

In operation of the present invention the equalizing valve here shown is assembled with a suitable packer, such as the rathole packer 15, and is connected to a drill stem 10, or a part of a tool with which the device is used, such for example as the housing of a formation testing tool. As the structure is lowered through the standing column of mud fluid within the well the tubular mandrel 11 and the sleeve 12 may assume the position indicated in Fig. 4 of the drawing and be locked by the engagement of the shoulder 27 of the head and the end of the splines 31 in the space 36, or if desired the mandrel and the sleeve may be locked with relation to each other, as shown in Fig. 1 of the drawing. If so locked no bypass of fluid will occur through the device. If the tool is locked and is lowered into the well in the condition shown in Fig. 2 of the drawing then fluid may freely equalize around and through the packer by reason of the fact that the perforations 21 in the mandrel 11 are in register with the passageway 22, and this passageway is in turn in communication with the perforations 25 of the packing nut. When the packer is lowered on to its seat as shown in Fig. 2, or when it is properly set within the well, it will be evident that the mandrel 11 and its head 26 may be rotated to bring its keyways 28 into register with splines 31 so that vertical movement of the mandrel may be accomplished. This will permit a downward movement of the tubular mandrel 11 with relation to the sleeve 12. This downward movement will force the mandrel 11 into the sleeve so that the perforations 21 will be closed in the body of the sleeve 12 as the lower end of the mandrel 11 encounters the upper end of the coupling 13. Such operations as may be desired are then carried out during which time the fluid column standing within the well above the packer will remain quiescent. Direct flow of entrapped fluid from the area below the packer may take place upwardly through the packer and the mandrel and into the tool or drill string generally indicated at 10 in the drawing. In the

event that it is desired to lock the mandrel and the sleeve with the bypass perforations 21 closed this is accomplished by a partial rotation of the mandrel 11 so that the shoulder 27 will come under the ends of the splines 31 and the keys 28 5 out of register with splines 31.

It will be seen that by the arrangement here shown it is possible to optionally establish or discontinue a bypass flow of fluid through a well packer and to lock the valve in its opened or 10 closed position by simple manipulation from the top of the well and to optionally open or close the valve.

While I have shown the preferred form of my invention, as now known to me, it will be understood that various changes might be made in the combination, construction and arrangement of parts by those skilled in the art, without departing from the spirit of the invention as claimed. 15

Having thus described my invention, what I 20 claim and desire to secure by Letters Patent is:

1. An equalizing valve for oil well tools comprising a sleeve valve unit, including a valve sleeve, a valve mandrel slidable within said valve sleeve, the valve mandrel and the valve sleeve 25 having ports which when moved to register will permit a flow of fluid through the mandrel and the sleeve, a packer attached to one of said valve elements, a supporting drill string attached to the other of said valve elements and by which relative movement between the sleeve and the mandrel may be effected, and means carried by the sleeve and the mandrel and adapted to be moved to interlocking positions whereby the sleeve and the mandrel will be locked against movement 30 with relation to each other when the valve is closed and when the valve is opened.

2. A well tool comprising a well packer, a valve structure comprising a valve sleeve adapted to be connected with said well packer, a valve mandrel reciprocating within said sleeve and adapted to be connected with a string of oil tools by which the valve structure and the packer are suspended within a well, the valve mandrel and the valve sleeve having ports through them adapted to be 40 moved to and from registering positions when the mandrel and the sleeve have relative vertical movement with relation to each other as produced by vertical movement of the supporting drill string, means splining the mandrel and the 45 sleeve together whereby the mandrel and the sleeve may have limited relative rotation with relation to each other, and interlocking means carried by the valve sleeve and the mandrel whereby the valve and the sleeve may be rotated 50 with relation to each other to lock the valve in a closed position.

3. A well tool comprising a well packer, a valve structure comprising a valve sleeve adapted to be connected with said well packer, a valve mandrel reciprocating within said sleeve and adapted to be connected with a string of oil tools by which the valve structure and the packer are suspended within a well, the valve mandrel and the valve sleeve having ports through them adapted 60 to be moved to and from registering positions when the mandrel and the sleeve have relative vertical movement with relation to each other as produced by vertical movement of the supporting drill string, means splining the mandrel and the 65 sleeve together whereby the mandrel and the sleeve may have limited relative rotation with relation to each other, and interlocking means carried by the valve sleeve and the mandrel whereby the valve and the sleeve may be rotated 70 with relation to each other to lock the valve in a closed position.

with relation to each other to lock the valve in a closed position.

4. A well tool comprising a packer carried by a string of pipe and adapted to be set in a well, 5 said packer having a passageway through it, a valve housing carried by the packer, a tubular mandrel therein and attached to the pipe string, means providing relative longitudinal movement of said mandrel and said valve housing, cooperating valve means on the mandrel and the housing whereby a bypass of fluid may occur through the packer and into the well when the valve is open and said flow will be interrupted when the valve is closed and cooperating means acting to rigidly lock the mandrel and the valve housing against relative longitudinal movement when said valve means is open and when said valve means is closed.

5. A well tool adapted to be connected with a 20 string of pipe and carrying a packer having a fluid passageway therethrough, a valve structure including a tubular housing carried by the packer, a tubular mandrel carried by the pipe string slideable within said housing and through which a fluid course is established from the packer to the drill string, means providing relative longitudinal movement of said mandrel and said valve housing, valve ports formed in the wall of the mandrel, sealing means therefor carried by said tubular 25 housing whereby when the tubular mandrel and the housing are in collapsed position with relation to each other the ports will be closed by said sealing means and when in their extended posi-

tion the ports will establish communication between the interior of the tubular mandrel and the well bore, and cooperating means between the housing and the tubular mandrel whereby said mandrel and housing may be locked against relative longitudinal movement in their collapsed and extended positions.

6. A well tool adapted to be connected with a tubular string of pipe and carrying a packer having a fluid passageway therethrough, a valve 10 structure including a tubular housing carried by the packer, a tubular mandrel carried by the pipe string slideable within said housing and through which a fluid course is established from the packer to the drill string, means providing longitudinal movement of said mandrel and said housing, valve ports formed in the wall of the mandrel, sealing means therefor carried by said housing whereby when the tubular mandrel and said housing are in collapsed position with relation to 20 each other the ports will be closed by said sealing means and when in their extended position the ports will establish communication between the interior of the tubular mandrel and the well bore, and cooperating means between the housing 25 and the tubular mandrel whereby said mandrel and housing may be locked against relative longitudinal movement in their collapsed and extended positions, and means transmitting rotational movement from the tubular mandrel to the 30 housing.

MORDICA O. JOHNSTON.
